UNITED STATES PATENT OFFICE.

NETTIE ILLOWAY, OF NEW YORK, N. Y.

HAIR-CURLER.

1,163,343.

Specification of Letters Patent. Patented Dec. 7, 1915.

Application filed June 28, 1915. Serial No. 36,691.

To all whom it may concern:

Be it known that I, NETTIE ILLOWAY, a citizen of the United States of America, residing at New York city, Manhattan borough, county and State of New York, have invented certain new and useful Improvements in Hair-Curlers, of which the following is a full, clear, and exact description.

This invention relates to an improvement 10 in hair-curlers of the variety employed by women in lieu of paper to hold strands of hair in curled formation over night or for a considerable length of time. As is well known, articles of this general character are 15 used instead of employing curling-irons.

My improvement pertains more particularly to the construction of a pliable curling device about which, or between the members of which, the strands of hair are 20 passed and afterward curled or twisted, the pliable nature of the curling agent making it possible to hold the strands in such twisted or curled formation.

I will now proceed to describe my invention 25 in detail, the essential features of which will be summarized in the appended claims, reference being had to the accompanying drawing, forming part hereof; wherein—

30 Figure 1 is a plan view of a hair curler embodying my improvements; Fig. 2 is an enlarged longitudinal sectional view of a portion of the curler, and Fig. 3 is an enlarged cross-sectional view, the section being taken on a line 3—3 in Fig. 1.

35 My improved curler consists of a strip of pliable wire covered by superposed layers of rubber and fabric, the wire being indicated by 1, the rubber coating by 2, and the 40 outer fabric covering by 3. To form the curler a strip of cable, constructed as above mentioned, is bent over upon itself to cause the ends to meet as at 4 (Fig. 1), after which a band 5, of leather or the like, is 45 passed around the members of the cable, intermediate the ends of the curler, to lie over the meeting ends of the cable, indicated as an entirety by 6. The band, or the strip forming the band, may be secured together 50 at its ends in suitable manner, as, for instance, by gluing or stitching. The numeral 7 (Fig. 3) indicates the point of secure-

ment of the ends of the strip forming the band 5. The band 5 is drawn tightly around the members of the curler to hold 55 them firmly together to prevent slipping and also acts as a stiffening element for the central portion of the curler. The rubber coating 2 tends to prevent the outer coating 3 from creeping thereby forming ridges 60 which would catch the hair. The outer covering 3 is smooth and will not catch the hair. That portion of the curler adjacent the ends 8 of the band 5 may be used to provide a clamping portion into which 65 strands of hair can be pulled and firmly held, said clamping portion being indicated by 9. The pliable nature of the curler permits it to be twisted into and retained in any desirable shape. Furthermore, each 70 end loop or portion 10 or 11 can be separated independently of each other. As the center portion of the curler is somewhat stiffer than the ends thereof, or in other words, is yieldable to a different degree, I 75 am able to flex the ends of the curler without flexing the center thereof. The center portion may be flexed by the application of more pressure than is required to flex the portions 10 and 11. The curler may of 80 course be manipulated in use in ways different from that described; for instance, the strands of hair may be twisted or curled around the central portion of my device, and the terminals 10 and 11 turned over 85 firmly against the curled strands of hair.

Having now described my invention, what I claim and desire to secure by Letters Patent is:

1. A hair-curler consisting of a pliable 90 cable bent over upon itself to form a loop, said cable having a coating of rubber applied thereto, a fabric covering applied to said rubber covering, and means to stiffen the curler intermediate the ends thereof. 95

2. A hair curler consisting of a pliable cable bent over upon itself to form a loop, each member of said loop being brought together intermediate the ends of the loop, and a band of leather or the like passing 100 around said loop at the point where the members thereof are brought together.

3. A hair-curler consisting of a pliable cable bent over upon itself to form a loop,

each member thereof being brought together intermediate the ends of the loop, and means to secure the ends of the cable and the body thereof closely together to form a central closed body and a loop at each end.

Signed at New York city, N. Y., this 25 day of June, 1915.

NETTIE ILLOWAY.
